UNITED STATES PATENT OFFICE.

ALBERT R. PRITCHARD, OF ROCHESTER, NEW YORK.

DESIGN FOR A HANDLE.

SPECIFICATION forming part of Design No. 25,409, dated April 21, 1896.

Application filed March 12, 1896. Serial No. 582,981. Term of patent 7 years.

To all whom it may concern:

Be it known that I, ALBERT R. PRITCHARD, a citizen of the United States, and a resident of the city of Rochester, in the county of Monroe and State of New York, have invented and produced a new and original Design for Handles, of which the following is a specification, reference being had to the accompanying drawings, in which—

Figure 1 is a front elevation of a handle, showing my design; and Fig. 2 is a side elevation thereof.

My design consists in the form and configuration and ornamentation given to the handle described herein and shown in said drawings.

In the drawings, A is the upper end piece, flared at the upper end a, as shown in Fig. 1, and ending below in a bead a'. From this end piece extends a horizontal rod B, having the annular beaded ornaments b at or about the middle thereof. The other end of the rod B extends upward and downward, the upper end thereof having the ornament b' somewhat

in the form of a snake-head. Opposite the end of the rod, on the thickened portion of the handle, is the oval escutcheon C. Thence the handle extends downward in the flattened portion D, gradually narrowing toward the bottom and provided on the outer side with the beads d. The lower end of the part D curls inward and upward and terminates in the pointed end d'. The lower portion of the handle is the C-shaped portion E, which is connected with the portion D by the circular bead e.

The various portions of my design connect with each other in a harmonious and ornamental manner, and the whole design is attractive and shapely.

What I claim is—

The design for a handle as shown and described.

ALBERT R. PRITCHARD.
